UNITED STATES PATENT OFFICE.

JOSEPH E. MERCER, OF INDIANAPOLIS, INDIANA.

TOILET-PAPER HOLDER.

1,204,810.

Specification of Letters Patent.

Patented Nov. 14, 1916.

Application filed August 5, 1916. Serial No. 113,379.

To all whom it may concern:

Be it known that I, JOSEPH E. MERCER, a citizen of the United States, residing at Indianapolis, in the county of Marion and State of Indiana, have invented a new and useful Toilet-Paper Holder, of which the following is a specification, reference being had to the accompanying drawings and to the letters and figures of reference marked thereon.

This invention relates to the type of appliance that is designed to hold roll-paper in convenient position to permit ready removal of portions of the paper, the invention having reference more particularly to a holder that is adapted for holding a roll of toilet paper.

An object of the invention is to provide an improved arbor on which to support a roll of paper, and improved means for supporting the arbor to constitute a removable projecting holder.

Another object is to provide a holder for roll paper that shall be so constructed as to permit quick changes when it is desired to replenish the holder with paper.

A further object is to provide a toilet paper holder that shall have the minimum number of simple and inexpensive parts and not liable to derangement, and which shall be durable and economical in use.

With the above mentioned and other objects in view the invention consists in the improved construction and in the parts and combinations and arrangements of parts comprised in a roll paper holder, as herein-after particularly described and further defined in the accompanying claims.

Referring to the drawings, Figure 1 is a side view of the improved paper holder and a roll of paper thereon, the latter being partially in section. Fig. 2 is a front elevation of the base part of the improved holder. Fig. 3 is a top plan of the improved holder. Fig. 4 is an end view of the improved arbor partially broken away. Fig. 5 is a vertical section on the line V—V of Fig. 3. Fig. 6 is a section on the line VI—VI of Fig. 2. Fig. 7 is a perspective view of the front part of the arbor. Fig. 8 is a section on the line VIII—VIII of Fig. 4, and Fig. 9 is a section on the line IX—IX of Fig. 2.

Similar reference characters on the different figures of the drawings indicate the

corresponding elements or features of construction herein referred to.

On the drawings the numeral 1 indicates a wall or partition which in many cases is composed of hard substance in which it is difficult to drill holes by hand power, and therefore the improved holder is adapted to be supported on the wall by means of a single screw. The holder includes a base which has a body portion 2 that preferably is disk-like and is dished in its normal rear side so that an annular bearing portion 3 is provided which is placed against the supporting wall. The middle of the body portion has a counter-sunk screw hole 4 therein to receive a screw 5 which is screwed into a suitable hole in the wall 1 and securely holds the base in position. The front of the base has a projecting portion 6 which is U-shaped and has a rib or flange thereon that extends inward, the rib or flange having a curved portion 7 that extends upward and vertical portions 8 and 9 that extend each toward the other to form guide bars, the faces 10 and 11 of which are straight and normally vertical. The front of the body portion of the base has a guide projection 12 thereon that extends downward from the curved portion 7 of the U-shaped projection.

The improved arbor comprises a cylindrical main part 13 which may be composed of wood and to which a metallic anchor-piece is secured. The anchor-piece comprises a disk-like main portion 14 that is placed against one end of the part 13 and has a counter-sunk screw hole 15 therein to receive a wood-screw 16 that is inserted into the part 13. The body part 14 preferably has a flange 17 thereon to embrace the adjacent portion of the wooden part 13. The part or portion 14 has a circumferential groove 18 therein to receive the ribs or flanges 8 and 9 and the curved portion 7, the groove forming a neck on which is a flange 19 adapted to engage the back or inner side of the ribs 8 and 9 to securely hold the arbor in place. The front end of the arbor is suitably provided with a flange to retain the roll of paper on the arbor. To this end a cap-plate 20 is provided which has a central screw hole 21 to receive a screw 22 which is inserted into the wooden part 13, the inner side of the cap-plate having a projecting rib 23 that embraces the adjacent portion of the wooden part. The cap-plate extends out-

- ward beyond the surface of the wooden part 13 to constitute a flange 24 to retain the paper roll in place. The retaining flange being permanently connected to the main 5 part 13 of the arbor, there are no small parts required to be handled with a risk of losing them. The paper roll 25 as will be understood has a hollow core 26 which receives the arbor and may be rotated thereon.
- 10 In practical use the core 26 of the paper roll has a sufficient frictional contact with its supporting arbor to prevent the roll of paper from turning too freely when portions of the paper are being removed from 15 the roll. When the core 26 is on the arbor its inner end is guided by the projection 12 and prevented from working over against the exterior of the U-shaped portion of the base. When the supply of paper is exhausted 20 the arbor is simply lifted upward until the flange 19 is separated from the guide bars 8 and 9, after which the core 26 is removed to permit the arbor to be inserted into the core of a full roll of paper. The 25 arbor is readily replaced to its normal position by simply placing the flange 19 behind the guide bars 8 and 9 until the neck 18 rests upon the curved portion 7 of the guide rib or flange.
- 30 Having thus described the invention, what is claimed as new is—
1. A roll-paper holder comprising a base having a central screw-hole and also two 35 guide bars on opposite sides respectively of the screw-hole, the base having also a stop

and a guide below the guide bars, an anchor-piece removably seated upon the stop and having a flange engaging the guide bars, a main part secured at one end to the anchor-piece, and a cap-plate secured to the opposite end of the main part. 40

2. A roll-paper holder comprising a base having two vertical guide bars and a stop device at the bottom of the bars, and a cylindrical arbor comprising a main part, an 45 anchor-piece secured to one end of the main part and having a flange to engage the guide bars, the anchor-piece being adapted to be supported upon the stop device, and a cap-plate secured to the opposite end of the 50 main part and extending outward beyond the surface of the main part.

3. A roll-paper holder comprising a base having a projecting front portion provided with two guide bars that extend each toward the other, the front portion having also a stop portion at the lower ends of the 55 guide bars and a guide projection extending downward from the stop portion and forward to the plane of the face of the projecting front portion; and an arbor having a neck to rest upon the stop portion, the neck having a flange thereon to engage the backs 60 of the guide bars.

In testimony whereof, I affix my signature in presence of two witnesses.

JOSEPH E. MERCER.
